UNITED STATES PATENT OFFICE.

FLOY D. KINCAID, OF LONG CREEK, OREGON.

DESIGN FOR A MILK-STRAINER.

59,232.

Specification for Design.

Patented Oct. 4, 1921.

Application filed July 22, 1920. Serial No. 398,327. Term of patent 14 years.

To all whom it may concern:

Be it known that I, FLOY D. KINCAID, a citizen of the United States, residing at Long Creek, in the county of Grant, State of Oregon, have invented a new, original, and ornamental Design for Milk-Strainers, of which the following is a specification, reference being had to the accompanying drawing, forming a part thereof.

The figure is a perspective view of a milk strainer, showing my new design.

I claim:

The ornamental design for a milk strainer as shown.

FLOY D. KINCAID.
